UNITED STATES PATENT OFFICE.

MARY M. HOVEY, OF FENTON, MICHIGAN.

DESIGN FOR A SLEEVE PORTION FOR BATH-ROBES.

SPECIFICATION forming part of Design No. 34,423, dated April 23, 1901.

Application filed January 30, 1901. Serial No. 45,896. Term of patent 7 years.

To all whom it may concern:

Be it known that I, MARY M. HOVEY, a citizen of the United States, residing at Fenton, county of Genesee, State of Michigan, have 5 invented and produced a new and original Design for the Sleeve Portion for a Bath-Robe; and I declare the following to be a full, clear, and exact description of the invention, such as will enable others skilled in the art to which 10 it appertains to make and use the same, reference being had to the accompanying drawing, which forms a part of this specification.

The drawing submitted herewith is a plan view of a sleeve portion for a bath-robe embodying my design.

As shown in the drawing, the leading feature of my design consists of an elongated sleeve portion *a*, formed with a straight side 15 1, a concave portion 2 toward one end thereof, 20 and a curved end portion 3, convexed between

the extremities of the curve, as shown. The upper end of the sleeve portion projects laterally from the lower portion on the edges opposite the edges 1 and 2. The sleeve portion is formed with a curved edge 4 below the 25 curved portion 3. Toward the lower end of the sleeve the edge opposite the edge 1 has also an offset portion 5. The sleeve portion has a straight lower edge, (indicated at 6.)

Having described my invention, what I 30 claim as new, and desire to secure by Letters Patent, is—

The design for a sleeve portion for a bath-robe as herein shown and described.

In testimony whereof I sign this specifica- 35 tion in the presence of two witnesses.

MARY M. HOVEY.
